PROJECTION VIEWER CABINET

Jerry T. Melton, Tampa, Fla., assignor to
Televue, Inc., Tampa, Fla.

Filed Feb. 24, 1970, Ser. No. 21,578

Term of patent 14 years

Int. Cl. D16—03

U.S. Cl. D61—1

FIG. 1

FIG. 2

FIG. 3

FIG. 4

FIG. 1 is a top plan view of a projection viewer cabinet, showing my new design.

FIG. 2 is a front elevational view.

FIG. 3 is a left side elevational view.

FIG. 4 is a right side elevational view.

The diagonally lined portion of FIG. 2 is provided to indicate the transparency of that portion.

I claim:

The ornamental design for a projection viewer cabinet, as shown and described.
